UNITED STATES PATENT OFFICE.

JOHN J. OTTO, OF CHICAGO, ILLINOIS.

BOAT.

Application filed May 28, 1919. Serial No. 300,387.

To all whom it may concern:

Be it known that I, JOHN J. OTTO, a citizen of the United States, residing at Chicago, in the county of Cook and State of Illinois, have invented certain new and useful Improvements in Boats, of which the following is a specification.

This invention relates in general to boats, and more particularly to the construction 10 of the bottom thereof and to the apparatus for propelling and controlling the direction of travel of the boat.

While I am aware that it has heretofore been proposed to propel and steer boats by 15 projecting fluid jets from the hull of the boat outwardly into the surrounding water, my present invention contemplates a practical application of this method of propulsion to a boat structure.

One of the primary objects of my invention is to provide a simple and practical manner of applying the necessary pipes and 20 the jet nozzles to the bottom of a boat, and to provide for covering and adequately protecting the pipes and nozzles by a steel covering comprising individual plate sections 25 or units which are capable of removal individually to permit access to the nozzles and pipes for purposes of cleaning or repairs.

Another object of my invention is to provide a simple and practical controlling apparatus by which the flow of fluid under pressure may be directed to any desired set 30 or sets of nozzles so as to propel the boat in any desired direction, thus enabling its movements to be controlled with ease and accuracy.

A further object of the invention is the provision of novel and improved nozzle structures by which the propelling fluid is delivered into the surrounding water to produce the most effective and efficient results.

Other objects and many of the attendant 40 advantages of my invention will be readily appreciated by those skilled in the art as the same becomes better understood by reference to the accompanying drawings.

Referring to the drawings,—

Fig. 1 is a side elevation of a boat embodying my invention;

Fig. 2 is a transverse sectional view there- 45 through, this view being somewhat diagrammatic in character;

Fig. 3 is a view looking at the bottom of 55 the boat with the false work and protecting sheathing removed;

Fig. 4 is a diagrammatic plan view of the boat showing the manner of delivering and 60 controlling the flow of fluid to the nozzles;

Fig. 5 is an enlarged fragmentary view of a portion of the boat bottom;

Fig. 6 is a side elevation of one of the controlling valves;

Fig. 7 is a sectional view through the 65 steering device;

Fig. 8 is a fragmentary sectional view of the relation between one of the nozzles and its protecting plate;

Fig. 9 is a similar view of a modified construction;

Fig. 10 is an end view of a circular multi-jet nozzle;

Fig. 11 is a longitudinal sectional view showing one arrangement of the nozzle jets;

Fig. 12 is a similar view showing a modified arrangement;

Fig. 13 is a sectional view showing the jet arrangement in a flat nozzle;

Fig. 14 is a similar view showing a modified jet arrangement;

Fig. 15 is a sectional view adjacent the delivery end of the nozzle shown in Fig. 13;

Fig. 16 is a similar view of a flat single jet nozzle;

Fig. 17 is a diagrammatic view showing the arrangement of the pressure pump and main controlling valve;

Fig. 18 is a sectional view through the controlling valves of the apparatus;

Fig. 19 is a longitudinal sectional view through the main controlling valve; and

Fig. 20 is a diagrammatic view showing the arrangement of the valve controlling dials.

Referring to the drawings, reference character 21 indicates generally a boat which may be of any desirable size and shape and equipped, as is customary with a keel 22. Near its forward end the keel is provided 100 with laterally disposed jet openings 23 and 24, respectively, and likewise, near its rear end, it is provided with similar laterally disposed jet openings 25 and 26. Jets of fluid, such as water, compressed air, or any 105 other fluid, are ejected under pressure from one or more of these sets of keel jets to move the boat laterally in a manner which will

be later described. The stern of the boat may be provided with the usual rudder if desired, or it may be equipped with a fluid pressure steering device 27, best illustrated in Fig. 7. This device comprises a cylindrical casing 28 divided transversely by a partition 29, the upper chamber above the partition being supplied with fluid under pressure through a pipe 31. The lower chamber is provided with a series of parallel circumferential slots 32 extending through an angle of at least 180 degrees, and within the casing there is disposed a rotatable pipe or tube 33 communicating with the upper chamber through a port 34 and provided below the partition with a series of nozzle members 35 projecting into the slots 32 and terminating substantially flush with the periphery of the casing which serves to protect the nozzle member against injury. For the purpose of strengthening the nozzles and also to exclude water from the interior of the casing, which would enter around the nozzles through the slots 32, I have provided an inner cylindrical member 36 through which the nozzles project and with which they have a snug fit, this member being carried by the nozzles and one or more arms 37 projecting from the tubular central portion 33. The top of the tubular member 33 is equipped with a wheel or disk 38 which may be operated through gearing, cables, or any other suitable mechanism to swing the member 33 and the nozzles in a horizontal plane in the casing. This wheel 38 is preferably detachably secured to the upper end of the member 33 and the bottom 39 of the casing is made removable to permit assembly of the parts. It will be manifest that fluid under pressure introduced to the steering device through the pipe 31 will issue in jets from the nozzles 35 into the surrounding water, and by turning the member 33 the lateral direction of the jets may be changed to steer the boat in the desired direction. These jets also act as propelling jets and when the boat is going straight ahead, this steering device acts as an auxiliary propelling apparatus to augment the propulsive effect of the main propelling jets, which will be later described.

The water-tight bottom of the hull is indicated in Fig. 2 by reference character 41 and over the outer face of this bottom I apply my improved fluid jet propelling apparatus. This apparatus may be incorporated in the bottom structure when the boat is originally built or it may be applied to old boats if desired. Over the outer face of the boat bottom proper 41, I provide a false work consisting of a series of stringers 42 and 43 extending longitudinally and transversely of the boat and securely united together and to the boat bottom 41 so as 60 to provide a rigid checker-work comprising

a series of rectangular shallow boxes 44 in which the jets and fluid supply pipes are arranged.

Referring now to Figs. 3 and 5, it will be observed that there is supported in this 70 false work a series of laterally extending pipes 45 equipped with rearwardly projecting nozzles 46 and a series of laterally projecting pipes 47 equipped with forwardly projecting nozzles 48. The streams 75 of fluid issuing from the nozzles 46 in a rearward direction are adapted to propel the boat forwardly and similar streams issuing from the forwardly projecting nozzles 48 are adapted to propel the boat rearwardly. The laterally extending pipes 45 are each connected with a longitudinally disposed pipe 49 extending longitudinally of the boat adjacent the keel thereof, the pipes 49 at opposite sides of the keel being 85 connected and supplied with fluid from a common supply pipe 51. Similarly the cross-pipes 47 are connected to longitudinal pipes 52 which in turn receive their supply of fluid from a common supply pipe 53. 90 Suitable mechanism, which will be later described, controls a supply of fluid so that it will be delivered to either the forward propelling nozzles or rearward propelling nozzles and thus, by supplying fluid under 95 pressure to one or the other sets of nozzles, the boat may be propelled forwardly or rearwardly at will.

For the purpose of protecting the nozzles and pipes against injury, I have provided 100 a steel covering or sheathing which is secured to the outer faces of the stringers comprising the false work. This sheathing is in the form of steel plates 54 each shaped to cover one of the sections of the false work, 105 and the plates are securely attached to the false work by countersunk lag screws or other suitable fastening means (not shown) which will leave a smooth exterior surface but will securely hold the plates in position, 110 and since the sheathing comprises a series of the sections or plates, it will be obvious that any one of them may be removed to permit access to the underlying nozzles and pipes or for purposes of repair or replacement when necessary.

The sheathing plates are provided with apertures through which the nozzles discharge their jets. In Fig. 9 a nozzle 48 is shown as fitting relatively snugly into its 120 protecting plate 54, the outer end of the nozzle being beveled off flush with the outer surface of the plate. Instead of thus beveling off the nozzle at an acute angle, it may, in some instances, be preferable to have the sheathing plates formed to provide depressions on their outer faces, as shown in Fig. 8, the nozzle in this instance projecting more squarely through the plate structure and since it is somewhat withdrawn from 130

the outer plane of the plate, it is less liable to injury.

The nozzles themselves may be of various shapes and constructions and in Figs. 10 to 16 inclusive, I have shown various practical forms. The cross-sectional view shown in Fig. 16 discloses a flat nozzle with a single flat orifice 55 similar to the nozzles disclosed in Figs. 2, 8 and 9. I have found, however, that the propulsive effect of a series of small jets is considerably greater than a single larger jet whose cross-sectional area substantially equals the aggregate cross-sectional area of the smaller jets. I prefer, therefore, to so construct the nozzle that it will deliver a series of small jets, and a cross-sectional view of such a nozzle is shown in Fig. 15 wherein the body proper of the nozzle is indicated by reference character 56 and the jet openings by 57. A longitudinal sectional view of this nozzle is shown somewhat diagrammatically in Fig. 13 and it will be observed from this figure that the jets issue in substantial parallelism. I have found, however, that the propulsive effect of the jets may be further increased by causing them to diverge as they issue from the nozzle, and in Fig. 14 a longitudinal diagrammatic section which will produce this effect is shown. In this instance it will be observed that the channels which terminate in the orifices 58 are so shaped that the jets issue in divergent directions, thus producing an expansive effect in the surrounding water and correspondingly increasing the propulsive effect of the jets.

In some instances it may be preferable to employ, instead of flat nozzles such as have been described, round nozzles such as are illustrated in Figs. 10 to 12, inclusive. Referring to Fig. 10, 59 indicates the body of a round nozzle which, as shown, is provided with a series of jet orifices 61. These orifices may discharge their jets in substantial parallelism as would be done by the nozzle illustrated in diagrammatic longitudinal section in Fig. 11, or the channels and orifices may be arranged as shown in Fig. 12 so that the jets issuing from the orifices 62 will diverge in all directions, thus increasing their propulsive effect, as has been previously explained.

The water or other fluid under pressure is supplied to the various nozzles hereinbefore described from a pressure pump and is distributed to the desired nozzles by certain controlling mechanism which will now be described. Referring first to Fig. 17, this view illustrates diagrammatically the pressure producing and a portion of the controlling mechanism. On this figure reference character 63 indicates the pressure pump which receives the fluid through an intake pipe 64 and delivers it through a delivery pipe 65 to a main controlling valve

66. The pump is equipped with the usual pressure regulator 67.

The main controlling valve 66, illustrated in Figs. 18 and 19, comprises a cylindrical casing 67 in which is mounted a rotatable cylindrical valve member 68 provided with an elongated port 69. The fluid under pressure is supplied to the bottom of this valve through the pipe 65 and the casing 67 is equipped with three discharge pipes 71, 72 and 73, respectively. When the valve member 68 is turned into register with the pipe 71, the fluid is discharged back to its original source and no propulsive effect in any direction is produced. When it is desired to move either forwardly or backwardly, the port 69 is brought into register with the pipe 72 through which the fluid is delivered to the bottom of the valve 74 which is somewhat similar in structure to the valve 66 and which controls the forward and backward movements of the boat. The rotatable member 75 of this valve is equipped with the port 76 which, when brought into register with the pipe 53, delivers the fluid into this pipe to the nozzles 48 through the piping previously described, thus propelling the boat backwardly. Upon adjustment of the valve to deliver the fluid into the pipe 51, the fluid is carried by the piping system previously described to the jet nozzles 46, thus propelling the boat forwardly. The valve is also connected with a discharge pipe 77 and when the valve is set to deliver fluid to this pipe no propulsive effect, either forwardly or backwardly, is produced.

The steering device 27 also receives its fluid from the pipe 72 through a branch 78 which, as will be apparent from Fig. 4, delivers the fluid directly to the steering device, but in case it should be desired to utilize the nozzles 46 or 48 without at the same time using the steering device, I have provided a cut-off valve 79 in the pipe 78 by which the flow of fluid to the steering device may be shut off when occasion requires.

The pipe 73 from the valve 66 delivers to the bottom of a valve 81, the casing of which is provided with a series of circumferential ports each connected with a pipe. The movable member 82 of the valve is provided with a port 83 adapted to register with any of the circumferential ports in the surrounding casing. Viewing Fig. 18 in connection with Fig. 4, it will be observed that pipe 84 leads directly to the nozzles 25 at the stern of the boat; pipe 85 leads to nozzles 26; pipe 86 is branched, one branch 87 connecting with pipe 84 and the other branch 90 connecting with pipe 87 which leads to nozzles 23; pipe 88 is also branched, one branch 89 leading to pipe 85 and the other branch 91 leading to pipe 92 which supplies the nozzles 24; pipe 93 is likewise

branched, one branch 94 leading to pipe 89 which connects with pipe 89 leading to pipe 85 and the other branch 95 leading to pipe 90 which connects with pipe 87 supplying nozzles 23; pipe 96 is connected by a branch 97 with pipe 87 which communicates with pipe 84 leading to nozzles 25 and is also connected by a branch 98 with pipe 91 connected with pipe 92 leading to nozzles 24.

10 Each of the pipes is equipped with a check-valve in the requisite positions as indicated by small circles in Fig. 4, so that fluid may flow in these pipes in one direction only.

In operation, if the port 83 of the valve 15 81 is brought into register successively with the various pipes upon rotation of the valve in a clockwise direction, the following operation will take place. Fluid delivered through the pipe 84 will cause the stern of the boat to be moved to the right, viewing Fig. 4. Fluid delivered through pipe 85 will cause the stern of the boat to move to the left. Fluid delivered through pipe 86 will be discharged from nozzles 25 and 23, 20 causing the boat to be moved bodily to the right. Fluid discharged through pipe 88 will be delivered from nozzles 26 and 24, causing the boat to be moved bodily to the left. Fluid discharged through pipe 93 will be delivered from nozzles 26 and 23, causing the boat to rotate in a clockwise direction about its central axis. Fluid delivered through pipe 96 will be discharged from nozzles 25 and 24, causing the boat to re- 25 30 35 40 45 50 55 60 65 70 75 80 85 90 95 100 105 110 115 120 125 130

In Fig. 6 I have shown a modified form of the valve 81 in which the various discharge pipes, instead of being arranged radially of the casing, are disposed in vertical alignment, and in this instance, the rotatable valve member 82, instead of having one port 83, is provided upon its periphery with a series of ports 99 which are adapted to be brought one at a time into registration with their respective discharge pipes so that by rotating the cylindrical member 82 the fluid may be directed into the desired discharge pipe to produce the requisite movement of the boat.

The various controlling valves may be operated and manipulated by any preferred mechanical or electrical apparatus, but the controlling board from which the various valves are operated is preferably located in the wheel-house of the boat and, as illustrating one practical form of controlling board, I have shown in Fig. 20 a layout consisting of five dials designated 101, 102, 103, 60 65 70 75 80 85 90 95 100 105 110 115 120 125 130

104 and 105, respectively. The dial 102 con-

trols valve 66. When the indicator is positioned as shown in this figure, fluid is discharged from the valve 66 through the pipe 71 and no movement takes place. When it is swung to position marked FB, fluid is delivered through pipe 72 to valve 74, and when it is moved to position LAT, the fluid is delivered through pipe 73 to valve 81. Assuming that the fluid is being delivered through pipe 72, the indicator on dial 105 may be moved to off or on positions to render the steering device 27 inoperative or operative, as desired, this indicator being connected to control the shut-off valve 79. In case this valve is open so that fluid will be delivered so to the steering device, the indicator on dial 103 may be manipulated to cause the delivery of the jets from the steering device in the requisite direction to steer the boat, this dial being connected with the wheel 38 of the steering device 27, and by movement of the indicator, will swing the nozzles 35 into position to impart the requisite direction of movement to the boat.

Dial 104 controls valve 74 and causes the fluid to be discharged idly through pipe 77 when the indicator is positioned as shown in Fig. 20, or, if the indicator is moved to position F the fluid is delivered through pipe 51 to the forward propelling nozzles, and when moved to position B, the fluid is delivered through pipe 53 to the rearward propelling nozzles.

The indicator on dial 101 controls valve 81 and by moving this indicator into the various positions marked on the dial, the fluid may be delivered singly to the nozzles 23, 24, 25 or 26, or to any desired combination of these sets of nozzles, in the manner previously explained.

It is believed that my invention, its construction, and its mode of operation will be understood and appreciated from the foregoing without further description, and while I have shown and described preferred embodiments, it should be obvious that the structural details are capable of a wide range of variation without departing from the essence of the invention as set forth in the following claims.

I claim:

1. In a boat, the combination of a hull, longitudinally and transversely extending stringers secured to the outer face thereof to form a checker-work over the bottom of said hull, pipes equipped with nozzles arranged between said stringers, and a series of removable plates fitted over said nozzles to protect the same and detachably secured to said stringers, said plates being provided with openings through which said nozzles discharge.

2. In a boat, the combination of a hull, stringers attached to the outer face thereof, nozzles arranged between said stringers, and

plates attached to said stringers to cover said nozzles, said plates being provided with openings into which the delivery ends of said nozzles fit, said plates being inwardly 5 depressed adjacent the nozzles to dispose the tips of said nozzles inside the plane of the outer face of said plates.

3. In a boat, the combination of a hull, a plurality of nozzles attached to the bottom 10 thereof, each nozzle comprising a series of elongated passageways each tapering from its intake to its delivery end, and plates attached to said hull and covering said nozzles, said plates being provided with openings 15 through which said nozzles discharge and inwardly depressed in the vicinity of the nozzles to dispose the discharge ends of said nozzles inside the plane of the outer face of said plates.

20 4. In a boat, the combination of a hull, a plurality of sets of nozzles disposed thereon and adapted to deliver jets of fluid for-

wardly and backwardly, a steering device comprising a series of vertically aligned nozzles adapted to be swung horizontally to deliver jets in desired directions, a casing within which said nozzles swing, provided with horizontal slots through which the nozzles project, a shell arranged within the casing and rotatable with the nozzles, and means 25 for delivering fluid under pressure to said nozzles.

5. In a boat, the combination of a hull, nozzles arranged over the outer surface 30 thereof, removable plates disposed over said nozzles to protect the same and provided with apertures through which said nozzles discharge, said nozzles being divided by a series of longitudinally disposed tapered 35 partitions to form a series of tapered discharge orifices, and means for supplying water under pressure to said nozzles.

JOHN J. OTTO.
